Application filed October 30, 1901. Serial No. 80,574. Term of patent 7 years.

To all whom it may concern:

Be it known that I, ALBERT PICK, a citizen of the United States, residing at Chicago, in the county of Cook and State of Illinois, have ⁵ invented and produced a certain new and novel Design for a Wine-Glass; and I do hereby declare the following to be a full, clear, and exact description of the same.

My invention relates to a novel design for a ¹⁰ wine-glass, the object being to provide a new and ornamental device of this character.

The accompanying drawing shows a wine-glass embodying my design in elevation.

My invention consists in a wine-glass having ¹⁵ a base, stem, and bowl, the base and stem being integral and consisting of the dressed

figure of a woman whose skirt is bell-shaped and forms the base upon which the wine-glass rests. The bowl of the glass rests upon the hat, and the arms of the figure are upraised, ²⁰ the hands grasping the rim on both sides.

My said design is very unique and effective and very ornamental.

I claim as my invention—

In testimony whereof I affix my signature in presence of two witnesses.
